UNITED STATES PATENT OFFICE

2,449,869

CONNECTOR

William F. Watson, Bronx, N. Y.

Application February 14, 1947, Serial No. 728,601

2 Claims. (Cl. 285—44)

1

This invention relates to new and useful improvements and structural refinements in connectors, more specifically, connector nipple assemblies such as are commonly employed for connecting pipes or tubes to hot water tanks, boilers, and similar enclosures, and the principal object of the invention is to provide a device of the character herein described, which may be easily and rigidly secured to such tanks, without the necessity of gaining access to the interior of the latter.

A further object of the invention is to provide a connector which may be quickly installed in position, even by unskilled persons.

Another object of the invention is to provide a connector which is simple in construction, neat in appearance, and which will readily lend itself to economical manufacture.

A still further object of the invention is to provide a connector which is otherwise well adapted for the purpose for which it is intended.

With the above more important objects in view and such other objects as may become apparent as this specification proceeds, the invention consists essentially of the construction and arrangement of parts as shown in the accompanying drawings in which:

Figure 1 is an elevational view of the invention in situ on a tank;

Figure 2 is a top plan view thereof;

Figure 3 is an elevational view, taken in the direction of the arrow 3 in Figure 1 and showing the invention partially broken away, and

Figure 4 is a cross sectional view of a nipple used in the invention, together with a pair of keeper rods associated therewith.

Like characters of reference are used to designate like parts in the specification and throughout the several views.

Referring now to the accompanying drawings in detail, the invention consists of a connector designated generally by the reference character 10, such as may be effectively employed in association with an enclosure, for example, a hot water tank, a boiler, or the like, indicated at 11.

The wall of the latter is formed with a suitable opening 12 and a tubular nipple 13 is positioned in this opening, as is best shown in Figure 3.

The nipple 13 is formed adjacent the inner end thereof with a pair of diametrically opposed apertures 14 and the outer end portion of the nipple is externally screw-threaded, as indicated at 15.

A pair of substantially U-shaped keeper rods 16 extend through the bore 17 of the nipple 13,

the mid portions 18 of the rods being of sufficient length (in relation to the nipple) that the outer end portions 19 of the rods project laterally from the outer end of the nipple, as will be clearly apparent.

The inner end portions 20 of the rods 16 project outwardly through the apertures 14 and engage the inner surface 21 of the tank 11, that is to say, after the nipple 13 has been positioned in the opening 12, the rods 16 may be inserted in the bore 17 and the rod portions 20 may be projected through the apertures 14, so as to facilitate this engagement.

Thereupon, a suitable gasket (preferably formed from resilient material) 22 is positioned on the nipple 13, one side of the gasket being concave, if necessary, so as to conform to the external curvature or contour of the tank 11. The nipple 13 also carries a clamping nut 23 positioned on the threaded portion 15, and a flat washer 24 is interposed between the nut 23 and the gasket 22, as will be clearly understood.

Finally, it will be noted that the mid portions 18 of the rods 16 are formed with a series of spaced notches 25, the purpose of which will be hereinafter more fully explained.

When it is necessary to connect a pipe (not shown) to the tank 11, this may be quickly and easily accomplished by the use of the invention, without the necessity of gaining access to the interior of the tank. It is only necessary to form an opening (indicated at 12) in the wall of the tank, so that the nipple 13 may be inserted in the opening, and the rods 16 may subsequently be applied to the nipple, substantially as described.

It will be noted that the U-shaped configuration of the rods will safeguard against the possibility of their being dropped into the tank through the nipple, which feature will be particularly appreciated when the installation is being made by unskilled hands.

In any event, when the rod portions 20 are engaged with the inner surface 21 of the tank 11, the gasket, washer, and nut, 22, 24, and 23, respectively are applied to the nipple, whereupon, by simply tightening the nut 23, the entire assembly will be firmly and securely retained in position on the tank. Needless to say, the purpose of the gasket 22 is to prevent the possibility of leakage, after the installation has been made.

The aforementioned notches 25 in the rod portions 18 will provide what may be referred to as cross-sectionally reduced areas having a lesser resistance to bending, whereby the outwardly projecting portions of the rods 16 may

be broken away after the nut 23 is tightened, substantially as indicated in the upper right-hand portion of the accompanying Figure 3. Thereupon, a suitable coupling nut (not shown) may be applied to the screw-threaded portion 15 of the nipple for the purpose of connecting the latter to a pipe, tube, or the like (also not shown).

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim is:

1. In association with an enclosure having an opening formed in the wall thereof, a connector comprising a tubular nipple positioned in said opening and provided adjacent the inner end thereof with a pair of diametrically opposed apertures, a pair of substantially U-shaped keeper rods extending through the bore of said nipple, the angulated portions at the inner ends of said rods projecting through said apertures and engaging the inner surface of said wall, the remaining end portions of said rods projecting

laterally from the outer end of said nipple, the outer end portion of said nipple being externally screw-threaded, a nut on said threaded portion, and packing means provided between said nut and the outer surface of said wall, the mid portions of said rods being formed with a series of spaced weakening notches.

2. In association with an enclosure having a wall formed with an opening, a connector comprising a tubular nipple positioned in said opening and having inner and outer ends, the inner end portion of said nipple being formed with laterally disposed apertures, a plurality of substantially L-shaped keeper rods positioned in said nipple and extending outwardly therefrom, said rods having angulated inner portions projecting through said apertures, and externally manipulable means on said nipple for urging the projecting inner portions of said rods against the inner surface of said wall.

WILLIAM F. WATSON.
